UNITED STATES PATENT OFFICE.

EUGENE J. RAY, OF BEVERLY, MASSACHUSETTS, ASSIGNOR TO UNITED SHOE MACHINERY CORPORATION, OF PATERSON, NEW JERSEY, A CORPORATION OF NEW JERSEY.

BUTTONHOLE-SEWING MACHINE.

Application filed December 20, 1919. Serial No. 346,306.

The invention relates to work spacing mechanism for buttonhole sewing machines and more particularly to mechanism for automatically spacing the work in machines 5 adapted for sewing a series of buttonholes in shoe flies.

In buttonhole sewing machines provided with means for automatically spacing pieces of work, such as shoe flies, the work 10 is moved between successive buttonholes a distance dependent upon the adjustment or setting of the spacing mechanism so that an equal spacing of the buttonholes is secured and the last buttonhole of the series is a 15 definite distance from the first buttonhole with any given setting of the spacing mechanism. It follows, therefore, that with a given setting of the spacing mechanism the variations in the length of flies, which in- 20 variably occurs with the present methods of manufacturing shoes, will result in the location of the last or top buttonholes at varying distances from the tops of the flies. This is objectionable since it is important, particu- 25 larly in the better classes of work, that the upper buttonholes be definitely located at substantially uniform distances from the upper edges of the flies for the same size and style of shoe.

It is the primary object of the present invention to enable the top buttonholes to be thus properly positioned in varying lengths of flies by the automatic spacing mechanism. To this end means is provided for securing 35 the adjustment, or setting, of the spacing mechanism requisite for locating the last buttonhole of the series to be sewed at a pre-determined point on the piece of work to be operated on. The requisite adjustment 40 is preferably secured by utilizing each piece of work to determine the adjustment of the spacing mechanism which will bring the last buttonhole at a point on the work pre-de- 45 termined by the operator. This may con- 50 veniently, and preferably is, done by means of a gage which, after the work has been located in position for sewing the first button- 55 hole, may be brought into register with the point on the work at which the last button- 60 hole should be located, and a cooperating 65 scale for indicating the adjustment of the spacing mechanism which will bring this point into register with the buttonhole sewing mechanism after a certain number of 70 buttonholes have been sewed.

To adapt the mechanism for indicating the settings for sewing different numbers of buttonholes in the same length of flies a series of scales may be arranged to be selectively brought into cooperative relation to 60 the gage.

While the invention relates primarily to buttonhole sewing machines as above indicated certain features are of more general application and may be embodied with ad- 65 vantage in other machines and mechanisms requiring similar or analogous adjustments or settings.

The various features of the invention will be readily understood from an inspection of 70 the accompanying drawings and the following detailed description of the mechanism illustrated therein.

In the drawings Fig. 1 is a plan view 75 showing so much of a buttonhole sewing machine and the automatic work spacing mechanism therefor as is necessary to illustrate the application of the present invention thereto. Fig. 2 is a front elevation and Fig. 3 is a side elevation showing the gage 80 and cooperating scale for indicating the adjustments of the spacing mechanism.

In the drawings a preferred form of the invention is shown applied to the buttonhole sewing machine fully shown and described 85 in application Serial No. 187,194, filed Aug. 20, 1917. This machine is provided with a buttonhole sewing mechanism adapted to cut and sew an eye-ended buttonhole, and a work spacing mechanism for automatically 90 spacing the work between successive button- 95 hole sewing operations, and controlling mechanism which stops the machine after a predetermined number of buttonholes have been sewed. The buttonhole sewing mecha- 100 nism comprises stitch-forming mechanism adapted to form overseam stitches, the upper needle of which is indicated at 2, and a travelling work clamp, the work supporting plates of which are indicated at 4, in Fig. 2. The work clamp is carried on a recipro- 105 cating clamp carriage indicated at 6 in Fig. 1, which also carries the work carrier 8, which is intermittently moved to automatically space the work between successive but- 110 tonhole sewing operations. The work carrier is provided with a work supporting plate 10 on which the shoe fly indicated at 12 is held by a series of spring clamping fingers 14 carried by a bar 16, which may

be operated by the operator to clamp or release the work. The work carrier is provided with a curved edge gage 18 against which the edge of the shoe fly is positioned 5 by the operator and is also provided with an open slot 20, which registers with the buttonhole zone of the fly. The work carrier is guided during its work spacing movements by fixed rolls 22 and 24 arranged to 10 engage the guiding slots 26 and 27 formed on the carrier. The slots are so shaped and the rolls so arranged that the fly is fed by the carrier in a path corresponding to the curvature of the edge guide 18 to properly 15 locate the series of buttonholes with relation to the edge of the fly. The mechanism for advancing the work carrier to space the buttonholes comprises a rack 28 provided with an arm 30 which is connected by a pivot 32 20 with a block 34 arranged to slide within a slot 36 in the carrier. The rack is engaged by a gear 38, which is driven from a worm wheel of equal diameter through connections which are operated upon by a cam 40 to 25 vary the movement imparted to the gear in accordance with the path of movement of the work carrier so that the requisite movements are given to the carrier to equally space the buttonholes along the irregular curved edge 30 of the work. The connections also include a coupling clutch which may be engaged or disengaged by a clamping nut 42 to permit the movement of the work carrier into position to properly locate the first buttonhole in 35 the series to be sewed. The worm wheel is engaged by a worm 44 which may be turned through a full revolution, or through varying fractions of a revolution, by an adjustable mechanism connecting the worm with a 40 spacing shaft 46. The distance through which the worm 44 is turned by a revolution of the spacing shaft 46 is determined by the adjustment or setting of an arm 48, the free end of which carries a pin adapted to be engaged with any one of a series of holes 50 45 in the index plate 52.

In operating this machine the operator places the fly which may or may not have been attached to the upper on the carrier 50 in such position that its edge fits the edge gage 18 and then operates the nut 42 to disconnect the gear 38 from the underlying worm wheel so that the carrier may be moved with relation to the spacing mechanism to 55 bring the lower end of the fly into such position with relation to the sewing mechanism that the lower buttonhole will be properly located in the fly. The nut 42 is then operated to reconnect the gear 38, and therefore 60 the carrier with the worm wheel and the connected spacing mechanism, preparatory to starting the machine to automatically sew and space a number of buttonholes determined by the setting of the mechanism 65 which controls the stopping of the machine.

In embodying the preferred form of the invention in this machine the location of the end buttonhole of the series with proper relation to the top edge of the fly is insured by the provision of a gage adapted to be brought into register with the point on the fly at which the last buttonhole of the series should be located and indicating upon a co-operating scale the adjustment of the spacing mechanism requisite for locating the last buttonhole at this point in the fly. With this mechanism applied to the machine the stitch-forming mechanism forms in effect a fixed gage which is brought into register with the point on the upper at which the first buttonhole of the series is to be located, and the gage above referred to forms a gage which is brought into register with the point at which the last buttonhole of the series is to be located, and the gage, by its position with relation to the cooperating scale indicates the setting of the spacing mechanism requisite for moving the work through the space between the gages in a pre-determined number of equal steps. In the construction shown the movable gage is in the form of a finger 54 pivotally mounted on a carrier slide 56, and adapted to be nominally swung up into a substantially horizontal position by a spring 58. The slide is mounted for movement on a guide bar 60 arranged above and corresponding in curvature to the edge gage 18 on the work carrier. The slide is provided with a second finger 62 arranged to register with a scale 64 on a plate 66, which is arranged above and corresponds in curvature to the guide bar and edge gage. The scale is provided with graduations corresponding to the holes in the index plate 52 and similarly marked, the holes in the index plate and the divisions on the scale being numbered 0 to 24 in the construction shown.

In order that the gage may be used to indicate the setting of the spacing mechanism requisite for sewing varying numbers of buttonholes in the same length of fly the scale plate 66 is provided with a series of scales 64, any one of which may be brought into register with the finger 62 on the gage carrying slide. To permit the movement of the scale plate to bring any of the scales thereon into position to register with the finger 62 the scale plate is mounted to slide vertically on a rod 68 and is held in adjusted position by a spring pressed retaining pin 70 adapted to engage notches 72 formed in the rod. A fixed finger 74 may be arranged to register with a scale 76 on the scale plate which indicates the number of buttonholes indicated in each scale 64 and will indicate the setting or adjustment of the mechanism which controls the stopping of the mechanism.

Assuming, for instance, that a fly of sub-

stantially the length indicated in Fig. 1 is to be operated upon and that eleven buttonholes are to be sewed in the fly, then after locating the fly and carrier to properly position the lower buttonhole as indicated in Fig. 1 the operator will move the scale plate 66 to bring the scale 64, corresponding to 11 in the scale indicating the number of buttonholes, into register with the finger 62 and 10 will then swing the finger 54 down into the position indicated in Fig. 2 and move it toward the right until its lower end registers with the point on the fly at which the upper buttonhole should be located. The finger 15 62 will then indicate on the scale 64 the proper setting of the arm 48 to properly space a series of eleven buttonholes and locate the last buttonhole of the series at the point on the fly which registers with the 20 lower end of the finger 54. Assuming that the finger 62 registers approximately with the division on the scale marked 18 then the pin in the end of the arm 48 of the spacing mechanism should be located in hole 18 of 25 the index plate 52 to properly position the eleven buttonholes in the fly held in the carrier. If a series of nine holes is to be sewed in a fly, the scale plate will be moved into the position indicated in Fig. 2 and if the 30 fly to be operated upon happens to be the shortest fly within the capacity of the machine the finger 54 will register substantially with the zero mark on the scale 64, as shown in this figure when it is in register with the 35 point on the fly at which the top buttonhole should be located. With the pin in the arm 48 in the 0 of the index plate 52 the work will be moved, at each operation of the spacing mechanism, the least distance within the 40 capacity of the mechanism and it will require eight successive operations of the spacing mechanism to move the work the distance between the stitch-forming mechanism and finger 54 indicated in Fig. 2.

45 While it is preferred to employ the specific construction and arrangement of parts shown and described in embodying the invention in the buttonhole sewing machine in the application above referred to it will be understood that this construction and arrangement is not essential to the broader features of the invention and may be varied or modified as found desirable or best suited to the construction and mode of operation 50 of the machine to which it is to be applied.

55 What is claimed is:

1. A buttonhole sewing machine having, in combination, buttonhole sewing mechanism, mechanism for spacing the work to sew a series of buttonholes therein, means for adjusting said mechanism to vary the spacing, and means for enabling an adjustment of the spacing mechanism to be secured requisite for locating the first and 60 last buttonholes of a series at points in the 65

work which are selected prior to the adjustment and may be varying distances apart.

2. A buttonhole sewing machine having, in combination, buttonhole sewing mechanism, mechanism for spacing the work to 70 sew a series of buttonholes therein, and means for indicating the adjustment of the spacing mechanism which will locate the last buttonhole of the series at a selected point in the work. 75

3. A buttonhole sewing machine having, in combination, buttonhole sewing mechanism, mechanism for automatically spacing the work to sew a series of buttonholes therein, and gaging means adapted to be brought 80 into register with the points on the work at which the first and last buttonholes are to be located for determining the adjustment of the spacing mechanism requisite for positioning the buttonholes at these points. 85

4. A buttonhole sewing machine having, in combination, buttonhole sewing mechanism, mechanism for automatically spacing the work to sew a series of buttonholes therein, a gage adapted to be brought into 90 register with the point on the work at which the last buttonhole is to be located after the work is positioned for the first button-hole, and cooperating means for determining the adjustment of the spacing mechanism requisite for locating the last button-hole at this point. 95

5. A machine having, in combination, mechanism for operating on the work, automatic spacing mechanism, gaging means 100 adapted to be brought into register with the points on the work at which the first and last of a series of operations of the operating mechanism are to be located for determining the required adjustment of the 105 spacing mechanism.

6. A machine having, in combination, mechanism for operating on the work, work spacing mechanism, two relatively movable gages adapted to be brought into register 110 with points on the work at which the first and the last of a series of operations of the operating mechanism are to be located, and a cooperating scale for indicating the required adjustment of the spacing mechanism. 115

7. A machine having, in combination, mechanism for operating on the work, work spacing mechanism, two relatively movable gages adapted to be brought into register 120 with points on the work at which the first and the last of a series of operations of the operating mechanism are to be located, and a series of scales adapted to cooperate with the gages in indicating the adjustment of the spacing mechanism requisite for different series. 125

8. A machine having, in combination, means for operating on the work, a work carrier, mechanism for advancing the car- 130

rier to space the work between successive cycles of operation of the operating mechanism, a gage adapted to be brought into register with the point on the work held by the carrier at which the last of a series of cycles of operations of the operating means is to be located, and a cooperating scale for indicating the required adjustment of the spacing mechanism.

10. 9. A machine having, in combination, means for operating on the work, a work carrier, mechanism for advancing the carrier to space the work between successive cycles of operation of the operating mechanism, a gage adapted to be brought into register with the point on the work held by the carrier at which the last of a series of cycles of operations of the operating means is to be located, and a series of cooperating scales for indicating the required setting of the spacing mechanism for different series.

10. A buttonhole sewing machine having, in combination, buttonhole sewing mechanism, a work carrier, mechanism for advancing the carrier to space the work between successive buttonholes, a gage adapted to be brought into register with the point on the work held by the carrier at which the last of a series of buttonholes is to be located, and a cooperating scale for indicating the required setting of the spacing mechanism.

11. A buttonhole sewing machine having, in combination, buttonhole sewing mechanism, a work carrier, mechanism for advancing the carrier to space the work between successive buttonholes, a gage adapted to be brought into register with the point on the work held by the carrier at which the last of a series of buttonholes is to be located, and a series of scales corresponding to different series of buttonholes, any one of which may be brought into cooperative relation with the gage to indicate the required setting of the spacing mechanism for that series.

12. A machine having, in combination, mechanism for operating on the work, automatic spacing mechanism, and means for determining by each piece of work the adjustment of the spacing mechanism requisite for locating the first and last of a series of cycles of operations of the operating mechanism at selected points thereon.

13. A buttonhole sewing machine having, in combination, buttonhole sewing mechanism, automatically acting spacing mecha-

nism for spacing the work between successive buttonhole sewing operations, and means for determining by each piece of work the adjustment of the spacing mechanism requisite for locating the last buttonhole of a series at a selected point on the work.

14. A buttonhole sewing machine having, in combination, buttonhole sewing mechanism, mechanism for equally spacing the work between buttonhole sewing cycles, and means for determining the setting of the spacing means by the points on the work selected for the first and last of a pre-determined series of buttonholes.

15. A buttonhole sewing machine having, in combination, buttonhole sewing mechanism, mechanism acting automatically to space the work equally between buttonhole sewing cycles, and means for determining the setting of the spacing means by the points on the work selected for the first and last of a predetermined series of buttonholes.

16. A buttonhole sewing machine having, in combination, buttonhole sewing mechanism, mechanism acting automatically to space the work to sew a series of buttonholes therein, means for adjusting said mechanism to vary the spacing, and means for enabling an adjustment of the spacing mechanism to be secured requisite for locating the first and last buttonholes of the series at points in the work which are selected prior to the adjustment and may be varying distances apart.

17. A buttonhole sewing machine having, in combination, buttonhole sewing mechanism, mechanism for spacing the work to sew a series of buttonholes therein, and means for indicating the adjustment of the spacing mechanism requisite for locating the first and last buttonholes of a series at points in the work which are selected prior to the sewing and may be varying distances apart.

18. A machine having, in combination, mechanism doing an operation on the work, mechanism acting automatically to space the work between successive operations thereon, means for adjusting said mechanism to vary the spacing, and means for enabling an adjustment of the spacing mechanism to be secured requisite for locating the first and last of the operations of the series at points in the work which are selected prior to the adjustment and may be varying distances apart.
